UNITED STATES PATENT OFFICE.

JAMES MARSDEN, OF WIGAN, ENGLAND.

DESIGN FOR A PATTERN-CHART.

SPECIFICATION forming part of Design No. 29,201, dated August 9, 1898.

Application filed June 8, 1898. Serial No. 682,958. Term of patent 14 years.

To all whom it may concern:

Be it known that I, JAMES MARSDEN, a subject of the Queen of Great Britain and Ireland, and a resident of Wigan, in the county 5 of Lancaster and Kingdom of England, have invented and produced a new and original Design for a Pattern-Chart, of which the following is a specification, reference being had to the accompanying drawing, forming a part 10 thereof.

The drawing is a plan view of a pattern-chart, showing my new design.

As shown in the drawing, the leading or material feature of my design consists in a 15 pattern-chart having represented thereon the novel arrangement of patterns for a lady's costume composed of jacket, vest, and skirt, as now described. As shown, the pattern-chart has the skirt parts A, B, C, and D, the 20 skirt-pocket E, the back side body F, the

front side body G, the skirt-pocket facing H, the top side sleeve H', the under side sleeve I, the jacket for part J, having inlays j, the jacket-facing K, the jacket-back L, having inlays l, the waistband M, the outside collar 25 N, the vest roll and facing O, the vest P, having inlays p', button-stand p², and darts p³, and the inside collar Q.

Having thus described my invention, the following is what I claim as new therein and 30 desire to secure by Letters Patent:

The design for a pattern-chart substantially as herein shown and described.

In witness whereof I have hereunto signed my name, this 12th day of May, 1898, in the 35 presence of two subscribing witnesses.

JAMES MARSDEN.
